UNITED STATES PATENT OFFICE.

GEORGE H. RUSSELL, OF FLORENCE, ALABAMA.

CATTLE-GUARD.

1,254,072.

Specification of Letters Patent. Patented Jan. 22, 1918.

Application filed August 30, 1917. Serial No. 188,986.

To all whom it may concern:

Be it known that I, GEORGE H. RUSSELL, a citizen of the United States, residing at Florence, in the county of Lauderdale and 5 State of Alabama, have invented a new and useful Cattle-Guard, of which the following is a specification.

The subject of this invention is a cattle guard intended for use on railways, and the 10 objects of the invention are, first, to provide a guard which will present an insecure footing to cattle or stock which may wander on the railway, second, to provide a guard that will not injure cattle that may be 15 stampeded and run over the same, third, to provide means for protecting the guard against injury, fourth, to provide a guard which may be readily formed from materials used by a railway, fifth, to provide a 20 simple and efficient guard.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without 30 departing from the spirit of the invention.

A practical embodiment of the invention is shown in the accompanying drawing, wherein:

Figure 1 is a plan view of a guard in 35 place on a railway;

Fig. 2 is an enlarged plan view of a guard section, parts being in section.

Referring to the drawing by numerals of reference:

40 A portion of a railway is indicated in Fig. 1 and is composed of cross ties 1 upon which are seated the rails 2.

The guard rests upon the cross ties 1 as shown, to which it is secured, and is composed of sections placed between the rails, and sections formed to rest without the rails upon the extending ends of the ties.

Each section is composed of side bars 3 formed with laterally extending attaching 50 lugs 4 positioned at each end of the lower edges of the bars. From the inner faces of the side bars 3 extend spaced bosses 5 be-

tween which are situated bosses 6 which are of larger diameter.

A retaining strip 7 is situated midway 55 between the side bars 3 and this strip is provided with spaced apertures to receive the tubes 8 and 9. The tubes 8 are slightly shorter than the tubes 9 and the bosses 5 of the side bars fit loosely into the ends of these 60 tubes. The ends of the tubes 9 receive the bosses 6 with a close sliding fit.

The bosses 6 and the side bars are apertured to receive bolts 10 upon the extending ends of which are threaded nuts 11. These 65 bolts pass through the tubes 9 and serve to bind the side bars 3 tightly in place against the ends of these tubes.

While bosses 5 and 6 have been described as projecting from the side bars, it is to be 70 understood that these bosses may be left off and the tubes 9 held firmly in place by the binding of the side bars thereagainst while other means may be employed for limiting the rocking of the tubes 8.

At each end of a guard is secured a protector in the form of an angled bar 12, one flange of which rests upon and is secured to a tie while the other flange rises therefrom. These plates will prevent broken 80 brake bars, or other parts which may be hanging from a passing train, hooking under the sections of the guard and destroying them.

In practice the device operates as follows: 85

When cattle or other live stock wander on the track and step on a guard the tubes 8 will rock upon the supporting strip and give the impression of an insecure footing thus keeping animals from wandering over 90 the track.

It is to be observed that these guards may be made from old boiler tubing thereby finding a use for this waste material and providing a cheap and effective guard. 95

Having thus described the invention, what is claimed as new and sought by Letters Patent, is:

A cattle guard composed of sections, each section comprising side bars, a central bar 100 substantially parallel with and between the side bars and provided with apertures, tubes extending through the apertures and retained by the side bars, each alternate tube

rockable on and transversely of the center bar, bosses of less diameter than the inside diameter of the tubes extending from the side bars and entering the ends of the rockable tubes to limit the movement of the tubes, and means for binding the side bars firmly against the other tubes.

In testimony that I claim the foregoing as my own, I have hereto affixed my signature in the presence of two witnesses.

GEORGE H. RUSSELL.
